UNITED STATES PATENT OFFICE.

ALBERT N. ROGERS, OF MIDDLEBORO, MASSACHUSETTS, ASSIGNOR TO UNITED SHOE MACHINERY CORPORATION, OF PATERSON, NEW JERSEY, A CORPORATION OF NEW JERSEY.

SHOE-BEATING MACHINE.

1,306,630.

Specification of Letters Patent. Patented June 10, 1919.

Application filed July 25, 1918. Serial No. 246,679.

To all whom it may concern:

Be it known that I, ALBERT N. ROGERS, a citizen of the United States, residing at Middleboro, in the county of Plymouth and 5 State of Massachusetts, have invented certain new and useful Improvements in Shoe-Beating Machines; and I do hereby declare the following to be a full, clear, and exact 10 description of the invention, such as will enable others skilled in the art to which it appertains to make and use the same.

This invention relates to shoe beating machines.

In the manufacture of welted shoes the 15 operator in trimming the inseam often cuts too close to the inseam so that the stitches break through the between substance when the shoe is worn. To avoid this difficulty and give greater strength to the shoe, it is 20 the practice in certain factories to leave the inseam untrimmed and to turn the marginal portion of the upper projecting beyond the inseam inwardly over the lip, or between substance, of the insole and press or beat 25 the same down against the body of the insole. This eliminates the necessity of trimming off the upper, and the marginal portion of the upper lying against the body of the insole assists in filling in the shoe bot- 30 tom. The operation of turning the marginal portion of the upper and beating the same down into position has heretofore been performed by hand and has required the expenditure of considerable labor and time.

35 One object of the present invention is to produce a shoe beating machine which will operate to turn the marginal portion of the upper projecting beyond the inseam inwardly over the lip, or between substance, 40 of the insole and beat the same down against the body of the insole in a certain and reliable manner.

Another object of the invention is to produce a shoe beating machine by which the 45 welt may be beaten out and the projecting marginal portion of the upper may be turned and beaten down into position in one operation.

With the above objects in view the invention 50 consists in the novel and improved constructions, arrangements and combinations of parts hereinafter described and particularly pointed out in the claims.

In the drawing, Figure 1 is a view in side

elevation of a portion of a shoe beating ma- 55 chine embodying the invention; Fig. 2 is a detail view partly in side elevation and partly in section illustrating the beating hammer and associated parts; and Fig. 3 is a detail view in front elevation illustrat- 60 ing the hammer.

The shoe beating machine illustrated in the drawing has the same general construction, arrangement and mode of operation of parts as the welt beating machine illustrated 65 and described in the patent to Hadaway, No. 875,171, dated December 31, 1907. The machine is provided with a welt support indicated at 2, the forward end of which is shaped to enter the crease between the upper and welt of a lasted shoe so as to support the welt on its upper surface and to 70 form a guide for the shoe, and a vibratory welt beating hammer 4 for engaging the welt as it is fed across the upper surface of 75 the welt support. The hammer is secured to the lower end of a rod 6 mounted to slide in a suitable guide bore in the forward end of the hammer lever 8. To cushion the blows delivered by the hammer upon the 80 welt, a coiled spring 10 surrounding the rod 6 within the bore in the hammer lever is interposed between a shoulder on the rod and the upper end of the bore. The downward 85 movement of the hammer in the forward end of the hammer lever is limited by means of a stop nut 12. The hammer lever 8 is pivoted upon a shaft 13 and is rapidly oscillated during the operation of the machine 90 to impart vibratory movements to the hammer. The machine is also provided with a welt slashing knife, indicated at 14, secured to the forward end of a reciprocating slide 16. With the exception of the hammer all 95 of the parts briefly described above have substantially the same construction, arrangement and mode of operation as the corresponding parts of the machine illustrated and described in the Hadaway patent referred to above.

100 The hammer 4 of the machine illustrated in the drawing is formed with the usual recess 18 to receive the knife as the knife is advanced to slit the welt, and is provided with beating faces 20 located on the op- 105 posite sides of the recess for engagement with the welt.

The hammer 4 differs from the hammer

of the machine illustrated in the Hadaway patent in that it is extended forwardly beyond the forward end of the welt support so that it projects beyond the between substance, or lip, of the insole of a shoe placed in the machine. At its forward end the hammer is provided with a projection 22 extending downwardly from the body of the hammer for engagement with the marginal portion of the upper. The lower face 24 of the projection 22 thus is located somewhat below the welt beating faces 20 of the hammer so that when the hammer is in its lowered position, with the welt beating faces 20 engaged with the welt, the projection 22 will press the marginal portion of the upper down against the body of the insole.

The hammer is cut away slightly intermediate the welt beating faces 20 and the projection 22, as indicated at 26, so that the hammer will not beat upon the stock along the inseam and break or weaken the seam.

With this construction, as the shoe is moved to advance the welt across the upper surface of the welt support, the welt beating faces 20 of the hammer engage the welt and beat the same out flat in the plane of the insole, and the projection 22 on the hammer engages the marginal portion of the upper projecting beyond the inseam, turns the upper inwardly over the lip of the insole and beats the same down against the body of the insole, as shown in Figs. 1 and 2. The welt support forms a guide for the shoe during the operation thereon and locates the shoe relative to the beating hammer so that the upper beating projection 22 will act within the lip or between substance of the insole and will not beat upon the same. The beating out of the welt and the turning and beating down of the marginal portion of the upper may thus be quickly performed in a reliable manner in one operation.

Having explained the nature and object of the invention, and having specifically described a machine embodying the same in its preferred form, what is claimed is:

1. A shoe beating machine, having, in combination, a guide for the shoe and a

beating device constructed and arranged to turn the marginal portion of the upper projecting beyond the inseam inwardly over the lip of the insole and to beat the same down against the body of the insole.

2. A shoe beating machine, having, in combination, a work support and a shoe beating device constructed and arranged to turn the marginal portion of the upper projecting beyond the inseam inwardly over the lip of the insole and to beat the same down against the body of the insole.

3. A shoe beating machine, having, in combination, a welt support, welt beating means and means for turning the marginal portion of the upper projecting beyond the inseam inwardly over the lip of the insole, and beating the same down against the body of the insole.

4. A welt beating machine, having, in combination, a welt support, a welt beating hammer and a projection on the hammer constructed and arranged to turn the marginal portion of the upper projecting beyond the inseam inwardly over the lip of the insole and beat the same down against the body of the insole.

5. A welt beating machine, having, in combination, a hammer having a welt beating face and a projection formed on the hammer having a beating face located below the welt beating face of the hammer and operating to turn the marginal portion of the upper projecting beyond the inseam inwardly over the lip of the insole and beat the same down against the body of the insole.

6. A welt beating machine, having, in combination, a welt support, a hammer arranged to extend forwardly beyond the inseam of a shoe, a welt beating face formed on the hammer opposite the welt support, and a downwardly extending projection formed on the forward portion of the hammer for turning the marginal portion of the upper projecting beyond the inseam inwardly over the lip of the insole and beating the same down against the body of the insole.

ALBERT N. ROGERS.
